UNITED STATES PATENT OFFICE.

LORUS T. HOLDAWAY, OF SAWTELLE, CALIFORNIA.

PUMPING MECHANISM.

Application filed March 15, 1926. Serial No. 84,817.

My invention relates to pumping mechanism, and more particularly to what is known as "mud pumps" in the oil drilling industry, and it has among its salient objects to provide an improved mud pump which can be operated successfully while certain portions of the mechanism thereof are being repaired or inspected; that is, the valves and other parts which are in constant contact with the mud and grit and which cause trouble are provided in duplex, either set being capable of being switched into operation while the other set is left free for inspection, repair or adjustments, thus making in one pump what is usually embodied in two pumps of this character.

In order to more fully explain my invention, I have illustrated one practical embodiment thereof on the accompanying sheets of drawings, which I will now describe.

Figure 1 is a vertical, longitudinal sectional view through a pump embodying my invention;

Figure 2 is a horizontal sectional view taken on the line 2—2 of Fig. 3;

Figure 3 is a vertical cross sectional view taken on line 3—3 of Fig. 1;

Figure 4 is a fragmentary sectional view on line 4—4 of Fig. 2;

Figure 5 is a similar view taken on line 5—5 of Fig. 3;

Figure 6 is a sectional view taken on line 6—6 of Fig. 5;

Figure 7 is a sectional view on line 7—7 of Fig. 1;

Figure 8 is a similar view on line 8—8 of Fig. 1; and

Figure 9 is a sectional view on line 9—9 of Fig. 3.

Referring now in detail to the drawings, the body comprises the upper part, 1 and a lower part, 2, with a cylindrical valve chamber, 3, therebetween, said valve chamber being of slightly conical, or tapering form, with cylindrical valve member of similar form, designated 4, therein, controlling communication between the upper part of the body with the lower part thereof. The upper part of said body is shown in longitudinal section in Fig. 1 and in transverse section, in Fig. 3, both being vertical sectional views. The upper part is divided by a longitudinally extending partition, 5, and

with a horizontal, longitudinal extending partition, 6, as indicated in said Figs. 1 and 3.

The lower part of said body, 2, is also provided with a longitudinally extending partition, 7, and each side of said partition is divided into two compartments, as 8, 8', and 9, 9', communicating at their tops with two cylindrical chambers, 10 and 11, in which work two pistons, 12 and 13, with the piston rods, 14 and 15, with conduits, as 16, through the piston rod and out through one side of each piston, at one end, and at its other end, said conduit turns out through the side of the piston rod and communicates with a pan-like member, through which the outer portion of the piston rods work, as seen in Figs. 1 and 5 and 6, for a purpose hereinafter again referred to. Said pan-like member is designated P.

Mounted in the four compartments, 8, 8', and 9, 9', are four flexible bag-like members, 17, 18, 19 and 20, connected at their mouths by means of a neck member, each designated 21, with the opposite ends of the two cylindrical chambers 10 and 11, as will be clear from the drawings. These cylindrical chambers 10 and 11, and said bags, 17, 18, 19 and 20, are partially filled with a fluid medium, such as oil or other suitable fluid adapted to be pumped from one pair of bags into the cylinder as the pistons are moved in one direction, thus collapsing the bags alternately and filling them alternately for the purpose of creating a pumping action within the four compartments, 8, 8', 9 and 9', for as the bag in one compartment is collapsed a suction or vacuum action is created within the compartment which draws into the compartment the mud mixture being pumped, and when said bag is expanded by the forcing of the oil, or other fluid into said bag, said mud mixture is forced out from said compartment, as will be understood from the showing. As any of the oil or fluid in the cylinders, 10 and 11, and the bags, 17, 18, 19 and 20, is forced by the piston rings, as where there might be excessive pressure, it will be drawn into the conduit, 16, in said piston and piston rod, and conveyed to the pan P, thus allowing the full stroke of the piston. As the piston is returned and the bag is completely collapsed, there will be sufficient suction created to draw some of

the oil through said conduit 16, from the pan P, and thus compensate for any excess or lack on either side of the piston. Check valves, as 21, are placed in the bottom of said pan, P, to control outlet from said pan through conduit members, as 22, 22, from the pan to the cylinders, as will be seen in Figs. 3, 5 and 6, the inlets into the cylinders being indicated in the cylinder 11, Fig. 1, 10 by the little circles, 22'. Thus oil or fluid forced past the pistons by excessive pressure will pass through conduits 16, 16, to the pan P, and from said pan said fluid or oil will be sucked through the conduit members, 22, 22, 15 back to the cylinders. Thus the oil or operating fluid used in the cylinders and bags is used over and over and is moved from one bag by each piston to the cylinder at one side, and at the other side of the piston is forced 20 into the other bag, as before referred to. This makes possible a maximum wear and utility of the pumping part of the apparatus, for the mud and sand and other matter which causes the wear and disturbance does 25 not get into the cylinders in which the pistons operate and does not get into the bags, but the breathing action, the expansion and contraction of the bags, causes the pumping action of the mud mixture as used in 30 connection with such pumps.

The valve member 4, it will be seen is provided with a series of ports therethrough and these are of different forms as may be required for making certain connections for 35 communications. At the left hand end of said valve member, Fig. 1, is a port, 23, seen in Fig. 3, opening communication between the left hand portion of the top part of the body, and the right hand portion of the 40 lower part of said body. When the valve member is turned a quarter turn, said port, 23, is in the reverse position, as indicated in light broken lines, Fig. 3, connecting the upper right hand part of the apparatus with the lower left hand portion thereof. The 45 next two ports through said valve member, designated 24 and 25, are shown in section, respectively, in Figs. 7 and 8. The next three ports through said valve member are 50 identical with the three just described, that is, ports, 28", 27 and 26, correspond with ports, 23, 24 and 25, respectively.

The intake and discharge openings to the apparatus are designated, respectively, 28 55 and 29, as seen in Figs. 1, 4, and 2, and as seen in Figs. 2 and 4, there is a two-way plug valve member, 30, which controls the inlet and the outlet from the different sides of the machine. As seen in Figs. 1, 2, 3 60 and 4, said valve is set so that the intake 28 leads into an intake chamber 28', thence through the intake valve, 31, into the chamber, 32, at the left hand side of the partition 5, Fig. 3, from whence it passes through the 65 port 23, and down into the chamber 9, being

drawn into this chamber by reason of the contraction of the bag, 19. On the expansion of said bag, 19, said mixture is forced out through the port 23, and up through outlet valve, 33, into the discharge chamber, 29', and thence out through the main discharge, 29. This action has taken place during the movement of the piston, 13, on its backward and forward strokes. At the same time said piston is moving on its suction stroke, that is, so as to take into the cylinder 11, the oil or fluid from bag 19, it is forcing oil or fluid out at the right hand side of the piston, 13, into bag 20, as seen in Fig. 1. This action is discharging the mud mixture from chamber or compartment 9', out through port 28", in said valve, 4, and up through outlet valve, 41 to the main outlet chamber 29' and outlet 29. The action just described represents the operation of one 85 side of the pump, with the double action caused by one complete movement of the piston from one end of the cylinder to the other, operating the two bags 19 and 20, as seen in Fig. 1. 90

In Fig. 2, which is an irregular horizontal sectional view, taken on the line 2—2, of Fig. 3, the chamber designated 32, in said Fig. 3, is so designated, 32, in Fig. 2, and is below the discharge valve, 33. This chamber 95 is used both as intake and discharge chamber. When bag 20, was expanded, as described, and the mud mixture was forced out through port, 28", it entered chamber 39, before passing through the outlet valve 41. 100

The other piston, 12, is operating alternately with piston 13, and its action is similar, using the ports, 24 and 27, in said valve 4, and on the suction stroke thereof movement is through inlet valves, 36 and 36', and 105 the chambers, 38 and 35, and out through discharge or outlet valves 40 and 34. This utilizes only one half of the upper, or valve mechanism of the pump, and all of the lower part of the pump. In case something happens to this valve mechanism of the pump, it is only necessary to turn the valve member 4, a quarter turn, and the plug valve 30, a quarter turn, whereupon the other valve mechanism, or half of the upper part of the 110 pump will function through the lower part of the pump. Referring to Fig. 2, the chamber or passage, 42, corresponds with 29, as the discharge passage. A suction chamber, 43, corresponds with suction chamber 120 28'. Chamber 44, corresponds to chamber 32, and chamber 45, corresponds to chamber 35, and chamber 46, corresponds to chamber 38, and chamber 47, corresponds to chamber 115 39. 125

I have provided each of the valve members, 4 and 30 with a rubber, or other suitable packing which is secured to the valve member, as by vulcanizing, in order that the valve may fit sufficiently close to prevent 130

sand or other foreign matter from getting into the valve seat. This packing or lining is designated R.

Thus it will be seen that the upper part 5 of the pump is of duplex character, or has two sets of valve controlling mechanisms, either one of which can be used with the lower half of said pump, so that in case one set goes wrong, the other set can be put to 10 use by simply turning the two valve members, 4 and 30, as before described. This makes it possible to continue the use of the pump while the valve set which is out-of-order is being repaired, and as the valve 15 mechanism constitutes the part of the pump which gets the most wear, it will be seen that I have two pumps in one, for the pumping mechanism, that is, the cylinders and pistons and bags in which the clean oil, or 20 other suitable fluid is used, has little wear and will outwear two sets of valve controlling mechanisms, provided for in the upper half of the pump, as here shown and described.

25 I do not limit my invention to the details of construction and arrangement shown and described, except as I may be limited by the hereto appended claims.

I claim:

30 1. In a pumping mechanism of the character referred to, in combination, a body portion having therein two sets of inlet and outlet control valves, a body portion having therein a pumping mechanism comprising 35 compartments having therein expansion and contraction bags, a cylinder communicating at its opposite ends with said bags, a piston operating in said cylinder, an operating fluid in said cylinder and bags and adapted to be 40 alternately pumped from bags to cylinders for the purpose of alternately expanding and contracting said bags in said compartments, a valve interposed between said compartments and said first mentioned body portion, said valve having ports therein for 45 selectively connecting said compartments with either of the sets of inlet and outlet control valves, whereby said pumping mechanism can be selectively connected through 50 either set of intake and exhaust openings.

2. In a pumping mechanism, in combination, a fixed upper body having intake and exhaust openings, with valves for controlling the same, a lower body having compartments 55 therein, bag-like elements in said compartments adapted to be expanded and contracted by an operating fluid, a cylinder and piston communicating with said bags and a fluid therein adapted to be pumped from cylinder 60 to bags alternately to expand and contract said bags within said compartment, a valve interposed between the upper fixed body and said lower body and controlling the communication between said compartments and 65 said intake and exhaust openings.

3. In a pumping mechanism, a fixed body having intake and exhaust openings, a plurality of compartments communicating with said openings, bag-like elements within said compartments adapted to be expanded and 70 contracted by filling fluid, a cylinder connected with said bag-like elements, a piston working in said cylinder, an operating filling fluid in said cylinder at opposite sides of said piston and adapted to be forced into and 75 drawn from said bag-like elements to expand and contract the same within said compartments, whereby said expansion and contraction within said compartments of said bag-like elements operates as a pumping mechanism through said intake and exhaust openings. 80

4. In a pumping mechanism, a body having intake and exhaust openings, two sets of intake valves and two sets of exhaust 85 valves adapted to be selectively set for controlling the intake and exhaust of said pumping mechanism, a plurality of compartments, a valve member interposed between 90 said compartments and said intake and exhaust openings, said valve being adapted to control communication between said compartments and through either set of intake and exhaust valves, bag-like elements in said compartments adapted to be expanded and 95 contracted, a plurality of cylinders connected with said bag-like elements, an operating fluid in said cylinders to be forced into and drawn from said bag-like elements, whereby to expand and contract the same to produce 100 a pumping action in said compartments, pistons for said cylinders for moving said operating fluid into and out of said bag-like elements.

5. In a pumping mechanism, in combination, a body having in one part thereof, two sets of intake and exhaust control valves with intake and exhaust openings adapted to be connected with either set of control valves, a valve for controlling the connection, 110 said body having one part provided with a plurality of compartments, a valve member for selectively controlling the communication between said compartments and either set of control valves to said intake and exhaust openings, a plurality of cylinders with pistons therein, bag-like elements in said compartments and connected in communication with said cylinders, an operating fluid in said cylinders to be forced into and drawn 115 from said bag-like elements to expand and contract the same, whereby to create a pumping action in said compartments through said valve member and said intake and exhaust openings through either set of control valves, substantially as described. 120

6. In a pumping mechanism, a body structure having intake and exhaust openings, means for creating a pumping action there-through, two sets of control valves for di- 125 130

- recting said pumping action through either of two sets of chambers, whereby either of said sets of chambers can be connected between said pumping means and said intake and exhaust openings, and a valve interposed between said pumping means and said sets of chambers, whereby said pumping action can be directed through either set of chambers and control valves.
7. In a pumping mechanism, in combination, means providing two courses of intake and exhaust with control valves for each course, means for creating a pumping action, a valve interposed to selectively control which course of intake and exhaust said pumping action will be directed through, whereby to make possible repair of one set of control valves while said pumping action is directed through another set of control valves.
8. In a pumping mechanism, a body having in its upper portion two courses of intake

and exhaust and two sets of valves for controlling the intake and exhaust through said courses, a pumping means comprising compartments adapted to be connected with either of said courses of intake and exhaust, a valve adapted for selectively connecting said pumping means with said courses of intake and exhaust, bag-like elements in said compartments, cylinders and pistons in communication with said bag-like elements, and an operating fluid in said cylinders to be forced into and drawn from said bag-like elements for creating a pumping action in said compartments, and means for equalizing the pressure of said operating fluid at opposite sides of said pistons by providing means for transferring fluid from one side to the other during the operation of said pistons.

Signed at Los Angeles, Los Angeles County, California, this 26th day of February, 1926.

LORUS T. HOLDAWAY
